UNITED STATES PATENT OFFICE.

CLINTON J. COFFMAN, OF EAST STROUDSBURG, PENNSYLVANIA.

FAUCET.

1,077,122.

Specification of Letters Patent.

Patented Oct. 28, 1913.

Application filed November 5, 1912. Serial No. 728,637.

To all whom it may concern:

Be it known that I, CLINTON J. COFFMAN, a citizen of the United States, residing at East Stroudsburg, in the county of Monroe 5 and State of Pennsylvania, have invented new and useful Improvements in Faucets, of which the following is a specification.

The invention relates to a faucet and more particularly to the class of lever operated 10 faucets.

The primary object of the invention is the provision of a faucet of this character wherein the valve thereof can be opened on pressing the drinking or other receptacle 15 against the lever, so that the fluid will be discharged from said faucet.

Another object of the invention is the provision of a faucet of this character which is simple in construction, reliable and efficient 20 in operation, strong, durable, and also one which is inexpensive in manufacture.

With these and other objects in view the invention consists in the construction, combination and arrangement of parts as will 25 be hereinafter more fully described, illustrated in the accompanying drawing and pointed out in the claim hereunto appended.

In the drawings: Figure 1 is a side elevation of a faucet constructed in accordance 30 with the invention. Fig. 2 is a vertical longitudinal sectional view of the same. Fig. 3 is a fragmentary bottom plan view.

Similar reference characters indicate corresponding parts throughout the several 35 views in the drawing.

Referring to the drawing by numerals, the faucet comprises a shell or casing 5, preferably constructed from metal, of any 40 approved pattern, having a downwardly extending discharge spout or nozzle 6, while the opposite end is formed with a reduced externally threaded portion 7, forming means to permit the attachment of the faucet to a pipe or supply medium, in the ordinary well-known manner.

Integrally formed within the casing or shell 5, is a partition 8, having an outlet aperture 9, about which is formed a valve seat 10, while in alignment with said aper-

ture at the top of the casing or shell 5, is a 50 threaded opening 11 in which is detachably fitted a nut shaped cap 12, whereby access may be had to the interior of the shell or casing. The cap 12 is formed with a central guide recess 13 in which is slidably engaged the upper end of a valve stem 14, carrying at its center a disk valve 15, the lower end of the stem being slidably fitted in a hole 16 located at the under side of the casing or shell, so that the lower end of the 60 valve stem will protrude exteriorly of the latter, for a purpose presently described.

Provided on the rear side of the spout or nozzle 6, are spaced parallel ears 17, between which is arranged a rearwardly extending swinging lever or arm 18, the same being connected to the ears by means of a pivot 20. The lever or arm is formed with a stop lug or lip 21 to engage the spout or nozzle 6, whereby to limit the downward 70 swinging of said lever or arm, which is arranged below the lower end of the stem 14 so that on the lifting thereof the latter will be raised to unseat the valve, the same being normally held to its seat by means of coiled 75 expansion spring 22 which surrounds the upper end of the stem and works against the cap and valve.

From the foregoing description taken in connection with the accompanying drawings it is thought that the construction and operation of the invention will be clearly understood, and therefore a more extended explanation has been omitted.

What is claimed is:

A faucet comprising a body having a discharge spout, a partition formed interiorly of the body and having an opening providing a valve seat, a valve engaging said opening and having opposed stems, one of said stems being slidably engaged in the body rearwardly of the spout and projected without the same, a removable cap mounted on the body above the opening and slidably engaged by the other stem, a coiled expansion 90 spring acting upon the valve to normally sustain the same seated, a bearing formed on the spout at the rear thereof, a lever piv- 95

85

otally mounted in the bearing and arranged in the path of movement of the stem projected without the body, and a lip formed on the lever and engageable with the spout to normally hold the said lever at a rearward inclination and projected below the mouth of the said spout.

In testimony whereof I affix my signature in presence of two witnesses.

CLINTON J. COFFMAN.
